[57] CLAIM

The ornamental design for a table for examination and therapeutic use, as shown and described.

DESCRIPTION

FIG. 1 is a perspective view of a table for examination and therapeutic use showing my new design, with a pair of removable inserts being shown in removed position;

FIG. 2 is a side elevational view thereof;

FIG. 3 is an end elevational view thereof;

FIG. 4 is a perspective view of the table for examination and therapeutic use shown in FIG. 1 but with the inserts in installed positions;

FIG. 5 is a side elevational view of the table for examination and therapeutic use shown in FIG. 4;

FIG. 6 is a bottom view thereof;

FIG. 7 is a perspective view of a table for examination and therapeutic use showing a second embodiment of my new design, the view differing from FIG. 1 in there being a showing of a hinging connection of an insert; and

FIG. 8 is a perspective view of a table for examination and therapeutic use showing a third embodiment of my new design, the view differing from FIG. 7 in there being a showing of hinged connections of a divided insert.

The arrows in FIGS. 7 and 8 indicate hinged adjustment of inserts.
